UNITED STATES PATENT OFFICE

2,409,387

CONTROL DEVICE

William A. Ray, Los Angeles, Calif., assignor to
General Controls Co., a corporation

Application February 15, 1943, Serial No. 475,859

3 Claims. (Cl. 200—138)

1

My present invention relates to condition-responsive control devices, such as thermostats, pressurestats, or the like, and has for an object the provision of a pair of such devices, mounted one upon the other, having unitary means for connecting the respective devices to apparatus to be controlled by them. This application is a continuation-in-part of my copending application, Serial No. 385,719, filed March 28, 1941.

Another object is to provide an arrangement of the character described in the preceding object, wherein one of the devices has a portion extended for connection to a relatively remote apparatus to be controlled, such as a valve or switch; the other of the devices being of the electric-circuit-controlling type and having electrical conducting means which forms a unitary part of the extended portion of the first-mentioned device.

A more specific object is to provide an arrangement, of the character described in the preceding object, wherein one of the devices is of the temperature responsive type and comprises a thermal bulb having a capillary tube portion extended for connection to relatively remote fluid pressure operated means to be controlled; the other of the devices, of the electric-circuit-controlling type, having conducting means which forms a unitary part of the capillary tube of the first-mentioned device.

Another object is to provide, in an arrangement of the character described in the preceding objects, means for automatically connecting the electric-circuit-controlling device to the conducting means upon mounting of the devices one upon the other. By providing (1) conducting means for the electrical device, which means forms a unitary part of the extended portion or capillary tube of the other device, and (2) means for automatically connecting and disconnecting the electrical device to and from the conducting means when the devices are respectively united or separated—the possibility of failure of the installer to make or break such connection is obviated. This is of particular importance when the electrical device is of the normally closed-circuit type and is employed as a safety or high-limit control, and hence failure to break the connection upon removal of the other device would permit the establishment of an unsafe condition. Likewise, if the electrical device is of the normally open-circuit type, failure to make the connection when the devices are assembled would not be apparent under normal conditions of oper-

2

ation, even although the electrical device would then be inoperative.

Other objects and advantages of the invention will be found in the description, the drawing, and the claims; and, for full understanding of the invention, reference may be had to the following detailed description and accompanying drawing, wherein:

Figure 1 is a longitudinal sectional view of condition-responsive apparatus embodying my invention shown by way of example, connected to control the operation of a gas heating system illustrated in diagram; and

Figure 2 is a fragmentary transverse section taken along the line 2—2 of Fig. 1.

Referring first to the burner control system shown in the lower portion of Fig. 1, the numeral 11 indicates a main burner which is connected by a conduit 12 to the outlet 13 of a fluid pressure operated valve generally indicated at 14. Connected in series with and ahead of valve 14 is another valve 15 of the rotary plug type, to the inlet of which is connected an electromagnetically controlled safety valve generally indicated at 16.

The valve 14 comprises a casing 17 having an opening in its top wall which is closed by a flexible diaphragm 18. Securing the diaphragm to the casing, and providing a pressure chamber 30 thereabove, is a housing 19. Extending from a pressure plate 20, secured to the underside of the diaphragm, is a stem 21 which is pivoted at its lower end on an intermediate portion of an arm 22. This arm is pivotally mounted at one of its ends on a pin 23 secured to the casing. Pivotally connected to another intermediate portion of arm 22 is a stem 24 for a closure member 25, which closure member is cooperable with a valve seat 26 provided in the bottom wall of the casing. A spring 27, compressed between a side wall of the casing and the free end of arm 22, is arranged to effect snap-action of the closure member in its opening and closing movements as arm 22 moves past center. So that this snap-action may

be fully effective, the upper and lower portions of stem 21 are interconnected by a lost-motion device 40. Urging the diaphragm and the closure member upward, is a compression spring 28.

The safety valve 16 comprises a casing 29 having a ported partition 30 providing a valve seat 31. Cooperable with this seat is a closure member 32 mounted on a rod 33, the free end of which sealingly extends through a side wall of the casing and is provided at its outer end with a compression spring 34 which urges the closure mem-

ber 32 toward its seat. Mounted in the safety valve casing 29 is an electromagnet 35 comprising a U-shaped core 36 which carries on one of its arms an energizing coil 37.

Mounted on the stem 38 of the plug valve is a cam 39 which, in the rotation of the plug valve, is adapted to engage the outer end of rod 33 and thereby move the closure member 32 away from its seat and into engagement with the pole faces of the electromagnet core 36. The closure member 32 is constructed wholly or in part of magnetic material so that when it is brought into engagement with the core, while the same is energized by passage of current through coil 37, the closure member will be magnetically retained in open position against the bias of spring 34. The electromagnet 35 is so designed that the closure member is magnetically held only when it is first brought into engagement with the core, no attraction of the closure member through space being contemplated. It will be noted that the cam 39 is so arranged with respect to the plug valve that the same is closed when the safety valve closure member is moved to its open position. The general combination of plug valve and safety valve, shown herein, is disclosed in Patent No. 2,297,718 granted to me October 6, 1942.

Referring now to the upper portion of Fig. 1 and to Fig. 2, there is shown, mounted in a wall 45 of a boiler 46 heated by the main burner 11, a combination thermostatic control device which comprises a cylindrical thermal bulb 47 and a bimetallic member 48. The thermal bulb is mounted in the boiler by means of a fitting 49 threaded in a nipple 50 welded in an opening through the boiler wall; a gland nut 51, threaded in the outer end of the fitting and closely surrounding the bulb, being provided for the compression of packing material 52 which serves to sealingly hold the bulb in position. The thermal bulb, the outer end of which is fluidly connected by a capillary tube 53 to the valve housing 19, is of conventional type, being of metal of high thermal conductivity and containing a volatile fluid which, upon predetermined rise of temperature of the boiler water, expands and thus produces a pressure within housing 19 above the diaphragm 18 sufficient to move the same downward against the bias of spring 28 so that the closure member 25 is brought into engagement with its seat.

The bimetallic member 48 is curved on an arc substantially concentric with the thermal bulb and is secured at one end to a boss 54 provided on the outer end portion of the fitting 49 so that it is in good heat-transfer relation to the bulb—the fitting 49 being of material having high thermal conductivity, such as brass. Insulatingly secured to the free end of the bimetallic member is a short metallic strip 55 which carries an adjustable contact screw 56 cooperable with a fixed contact member 57 secured to another boss 58 formed on the outer end portion of fitting 49; the contacts 56 and 57 being in continuous engagement under normal conditions. The contact screw 56 is electrically connected by the strip 55 and a wire 59 to a female electrical connector 60 insulatingly mounted on the flange portion of fitting 49; a similar female connector 61, mounted directly on an adjacent portion of the fitting flange, serving as electrical connecting means for the grounded contact member 57. Enclosing the bimetallic member is a cap 62 which is attached to the fitting 49 by three screws 63.

Around the capillary tube 53 of the thermal bulb 47 is electrical conducting means comprising

ing a sleeve 64 of woven wire which is electrically insulated from the capillary tube by a sleeve 65 of rubber or other suitable material. Molded on the outer end portion of the thermal bulb, and surrounding the adjacent end of the capillary tube, is a head 66 of insulating material such as Bakelite. Carried by this head is a pair of connector pins 67 which are cooperable respectively with the female connectors 60 and 61 and extend through suitable openings in cap 62; the pin which cooperates with the insulated connector 60 being connected by a wire 68 to the conducting sleeve 64, the other pin which cooperates with the grounded connector 61 being connected by a wire 69 to the capillary tube 53. By the arrangement described, the thermostatic control device constituted by the bimetallic member 48 is automatically connected to the conducting means, comprising sleeve 64 and capillary tube 53, when the thermal bulb is mounted on the fitting 49.

For the energization of the electromagnet 35, there is provided a thermoelectric generating device 70 comprising a pair, or plurality of pairs, of thermocouple elements contained within a protecting sleeve 71. The upper, or "hot junction" end of this device is arranged to be heated by the flame of a pilot burner 72 mounted on the main burner 11, for the ignition of which it also serves; the pilot burner being connected by a pipe 77 to the outlet of the safety valve 16. One lead of the thermoelectric generating device is connected by a wire 73 directly to one terminal of the electromagnet coil 37; the other lead of the device being connected by a clamp 74 to the capillary tube 53, and the other terminal of the coil by a wire 75 and clamp 76 to the conducting sleeve 64. By these connections, the energizing circuit of the electromagnet is placed in series with the contact members 56—57 of the bimetallic thermostatic device, these members being in continuous engagement at all normal operating temperatures of the boiler.

With the parts in the positions shown in the drawing, fuel supply to both the main burner 11 and the pilot burner 72 is obstructed by the safety valve closure member 32. To initiate operation of the system, the plug valve 15 is rotated from its open position, as shown, to a closed position wherein engagement of cam 39 with the end of rod 33 moves closure member 32 away from its seat and into engagement with the pole faces of core 36, whereupon fuel can flow through pipe 77 to the pilot burner 72 where it is lighted. The plug valve is manually retained in safety-valve-opening position until the thermoelectric device 70 has become sufficiently heated by the pilot burner flame to generate current in an amount sufficient to cause the electromagnet to hold the armature-closure member 32 in the position shown by the broken lines. When this occurs, the plug valve may be returned to its open position, fuel then passing to the automatic valve 14 which, if the water in the boiler is relatively cold, will be in open position on account of the contraction of the fluid in the thermal bulb 47. Fuel can therefore then flow to the main burner 11 where it is ignited by the pilot burner flame. When the temperature of the boiler water reaches a predetermined degree, the pressure of the fluid in the thermal bulb, applied to the diaphragm 18, effects closure of the automatic valve and hence extinguishment of the main burner. Upon resultant cooling of the water, the automatic valve reopens under the force of spring 28 due to reduction of fluid pressure

above the diaphragm; recycling of the valve maintaining the temperature of the water between predetermined limits.

If, due to faulty operation of the automatic valve or its control means, or from other causes, the temperature of the water rises to an abnormal degree, resultant outward warping of the bimetallic member 48 effects disengagement of the contact members 56-57 and thereby deenergization of electromagnet 35. The safety valve closure member 32 is thus permitted to return to its seat under the force of spring 34. Fuel flow to both the main and the pilot burner is therefore obstructed and the system must be "manually reset" as described above in order to reinitiate operation after the cause of the failure has been corrected. The bimetallic member, being in intimate thermal contact with the fitting 49 and insulated from the surrounding atmosphere by the cap 62, is at all times substantially at the temperature of the boiler water. By the angular arrangement of contact member 57, a wiping action occurs in the relative movement of the contacts.

An additional safety feature is provided by the pilot-burner-heated thermoelectric generating device. If the pilot burner should be accidentally extinguished, upon cooling of the thermo-electric device the resultant cessation of current generation effects deenergization of the electromagnet and the safety valve closes.

If for some reason the thermal bulb is removed from the fitting, the electrical circuit of the bimetallic thermostatic device is automatically broken, thereby effecting release of the safety valve closure member 32 to closed position. If such automatic disconnecting means were not provided, and if one were to fail to break the circuit of the safety valve in some other way, upon cooling of the thermal bulb the valve 14 would open and heat would be supplied to the boiler, with the possibility that the same would be damaged, since the water would then be below the level of the thermostat fitting. This safety feature of the

invention does not depend entirely upon the provision of the separable connectors 60-61 and 67, since, if manually connectable means, extending between the bimetallic unit and the conductor means 64, 53, were substituted therefor, these connections would have to be broken in order to remove the thermal bulb. Obviously, other means could be provided for effecting the safety disconnection, such as for instance means carried by the thermal bulb and cooperating mechanically with the bimetallic member.

While I have herein shown and described a specific embodiment of my invention, I wish it to be understood that modifications may be made without departing from the spirit of the invention, and that I intend therefore to be limited only by the scope of the appended claims.

I claim as my invention:

1. In combination: a first temperature-responsive control device comprising a thermal bulb having a metallic capillary tube extending therefrom for connection to relatively remote fluid pressure operated means to be controlled by the device, a second temperature-responsive device adapted to control an electric circuit and mounted on said thermal bulb in good heat-transfer relation thereto so that both of said devices are substantially equally thermally affected, and a pair of electrical conductors for connecting said second device in said circuit, one of said electrical conductors being formed in part by said capillary tube and the other comprising an element insulatingly supported by the tube.
2. The combination defined in claim 1 wherein said other of said electrical conductors comprises conductive material encircling said capillary tube and electrically insulated therefrom.
3. The combination defined in claim 1 wherein said other of said electrical conductors comprises a sleeve of woven wire encircling said capillary tube and electrically insulated therefrom.

WILLIAM A. RAY.
